UNITED STATES PATENT OFFICE.

JULES LEROY, OF PARIS, FRANCE.

TWO-STROKE INTERNAL-COMBUSTION ENGINE.

Application filed July 10, 1920. Serial No. 395,338.

To all whom it may concern:

Be it known that I, JULES LEROY, citizen of the Republic of France, and residing at Paris, France, 12 Rue Jouffroy, have invented Improvements in Two-Stroke Internal-Combustion Engines, of which the following is a specification.

The invention may have various industrial applications (automobile, aviation, marine and other purposes), and it includes the scavenging by compressed air, the admission of the explosive mixture by compression, the starting by compressed air, the pneumatic braking of the motor; the said invention, further, includes a special distribution mechanism for the motor and for the pump and special devices for actuating the parts ensuring the control of the said distribution mechanism.

In order to render intelligible the description of the said invention, it is represented in the accompanying drawings as follows:

Fig. 1 shows a transverse section through the axis of a cylinder.

Fig. 2 shows a longitudinal section through the axis of the engine.

Fig. 3 is a view in elevation of the engine on the exhaust side.

Fig. 4 is a view in elevation of the engine on the admission side.

Fig. 5 shows a sectional elevation of a modified construction of the system according to the present invention.

Fig. 6 shows a detailed view on the line VI-VI of Fig. 8 and represents the distributors applied respectively to the motor and to the pump.

Fig. 7 shows a detailed view of one of the elements of these distributors.

Fig. 8 shows a sectional elevation of the upper part of a modification in the construction of the motor.

Fig. 9 shows a sectional elevation at an angle of 90° in regard to Fig. 8 of this modification.

The Figures 1 to 4 show a cylinder 1 provided with two compression chambers 2, 3 and in which the motor piston 4 travels, connected by means of a hollow shaft 5 to a piston pump 6 serving as a sliding guide and travelling in the body of the pump 7. This piston pump 6 is connected in turn by means of a rod 8 to one of the cranks of the crank-shaft 9, which cranks are (in the motor shown) placed at an inclination of 120° to each other.

The crankshaft 9 is enclosed in a gear case 11 and has at one end a fly-wheel 12 (this fly wheel can be dispensed with in the case of a three cylinder machine) and at the other end a spur-pinion 13 which controls the distribution by means of the chain 14 kept stretched by aid of the pinion 15. This chain actuates the magneto 16 and the water pump 17. The gear case 11 is connected rigidly to the motor block by means which render the fixture secure, enclosing and holding fast between them as a fixture the pump body 7 and the plugs 20. The cylinder block is surrounded by a circulating water supply 21, the chamber for which is closed at its upper part by means of the cover 22 secured in place by the studs 23.

Between the cylinder block and the pump body the plugs 20 are interposed for the water circulation and they form the bottom of the cylinder for the lower explosion chamber 3. The said bottom is moreover provided with the stuffing box 24 about which it forms a tight joint for the passage of the piston rod 5.

Midway the ends of each motor cylinder 1 is arranged the exhaust port 25 connecting with a passage 26 closed in its course alongside the cylinder block by a cover plate 27. Each compression chamber 2, is provided with a sparking plug 28, 29 which gives one spark at each stroke and with an admission valve 30, 31 controlled by a cam 32 keyed upon the shaft 33. This cam puts the cylinder 1 into communication with the passage 34-35 (leading to the carburetor once at each revolution of the crankshaft).

The lubrication of the cylinder is ensured by an oil supply under pressure through the tube 36. The tubes 37, leading from the chamber 38, serve for the scavenging and for the starting by the compressed air. They correspond to independent chambers, each of which has a valve 39 controlled by a cam 40 for the scavenging and 41 for the starting. The compressed air necessary for these actions arrives from the high pressure reservoir 42, through a tube 43 and may be retained in case of need; this reservoir is supplied from the pumps 7 at the moment of the braking.

The cam shaft 33 is supported by suitable uprights and in the interior of this shaft there is placed another upon which are keyed the starting and scavenging cams 41 and 40, which shaft can be displaced by sliding

in the holding mechanism in order to set the cams above mentioned at any moment required over against the valves 39.

Upon the pump body 7 is fixed a collector 44 having in the axis of each pump an automatic suction valve 45, and a compression valve 46; this latter valve can be fixed upon its seat at the moment of the braking by means of a cylindrical axis 47 bearing 10 a locking cam 48 and controlled by a lever 49. This collector is in communication with the low pressure reservoir 50 which supplies air to the carburettor; this low pressure reservoir provided with a safety valve 51 15 and an air inlet 52 for the scavenging.

Upon the main collector 44 is fixed a little secondary collector 53 for the collection of compressed air during the braking (at which time the valves 46 are closed). This 20 secondary collector is provided with inlets closed in normal working by ball valves 54, said inlets when opened placing each pump body 7 in communication with the collector 53; the said collector is also in communication, by means of the tube 55, with the high pressure reservoir 42 which has an outlet plug and a safety valve 56; reservoir 42 is connected to the valves 39 by the pipe 43. The petrol reservoir 58 is also under pressure. The carburettor 59 is adjustably connected to the pipes 34 held in place against the cylinder block by a holder 60.

The normal operation of the motor is as follows:

35. Taking the motor at the point at which it is shown in Figures 1 and 2, at this moment the motor piston 4 is at the upper dead point (the motor rotates to the right in the direction of the hands of a watch); and the 40 spark which has been produced by the upper sparking plug 28 several millimetres before the end of the stroke has ignited the charge which was compressed in the explosion chamber 2; the motor piston 4 is driven 45 towards the bottom of its course, carrying with it the pump piston 6, which draws in fresh air from outside for two cylinder charges by means of the automatic valve 45. The motor piston 4, on descending, has uncovered the outlet port 25 through which 50 the burned gases escape as soon as these are nearly discharged, the cam 40 opens the scavenging valve 39 and non-carbureted compressed air reaches the cylinder through 55 the pipe 37 and sweeps out the remaining burned gases.

The same result may be obtained by means of the starting cam 41, the compressed air in either case remaining in the pipe 60 37 until the pressure has fallen in the interior of the cylinder 1 to allow it to penetrate into this latter. The scavenging has for its object to separate the entering charge from the escaping charge, and to cool the end of 65 the motor piston 4 and the cylinder. When

the burned gases are completely discharged, the cam 32 operates in its turn the admission valve 30, which puts the channel 34 containing the carbureted gas into communication with the cylinder 1; the cylinder fills 70 with explosive mixture (the scavenging valve 39 having been closed shortly before the opening of the admission valve 30) and the admission valve 30 remains raised during the rise of the piston until this latter 75 has again closed, by covering it, the exhaust port 25 so as to ensure a charge as complete as possible. The admission valve 30 must not return to its seat until the gases have no further momentum and tend to flow 80 back into the channel 34. The piston continuing to rise, the compression continues and terminates at the upper dead point; the ignition occurs a little before this point is reached as previously explained and the cycle 85 continues.

The same sequence occurs exactly at the other end of the piston, but delayed 180°. During this time the pump piston has risen, the valve 45 has been closed, the air has been 90 forced into the collector 44, has passed through the back pressure valve 46 and has reached the low pressure reservoir 50.

The second and the third cylinders operate in like manner but with a respective delay as against the first cylinder of 120° and 240°; in other words as there are two explosions per cylinder and per revolution, one explosion takes place at every 60°. To obtain this result the engine cylinder 1 is 100 supplied with carburetted gas as follows:

The air drawn in by the pump 7 is forced through the collector 44 into the low pressure reservoir 50 which is placed in communication with the passage 34, distributing the air passing through the jet of the carburettor.

This carburetted mixture is then distributed to the engine cylinder 1, passing through the channels 34, 35 and the control valves 30, 31 at the required moment, as has been already explained.

When the lever 49 is actuated to operate the locking cam 48 of the shaft 47, the said cam closes the back pressure valve 46 and the air drawn in by the pumps 7 is compelled, in order to escape, to raise the ball 54 and to pass through the collector 53, which delivers it to the high pressure reservoir 42.

This air which has been thus stored up is intended to serve for starting the motor. In fact if, by means of a valve the air of the reservoir 42 is allowed to flow into the tube 37, it passes to the valves 39, one of which controls admission of the air to the compression chamber 2 and the cam 40 of the shaft 33 causing the raising of this valve a little after the passage of the upper dead point of the motor piston 4, the compressed air can flow through 120 125 130

the tube 37 and arrive in the compression chamber 2 whence it forces the piston 4 towards the lower dead point, thus starting the motor. The carbureted air being distributed at the same time to the cylinders 1, the explosions take place as soon as the engine turns quickly enough to cause the magneto to give a sufficiently hot spark. The engine having started it is only needful to shut off the high pressure air passage by closing the valve 31 upon the supply tube to the cylinder.

This high pressure air can also serve for the scavenging after having passed through a reducer in the cases in which the air from the low pressure reservoir 50 used in the ordinary way would not be sufficient.

The braking is obtained by turning, by means of a coupling bar, all the levers 49 of the collector 44, which action causes the closing of the compression valves 46 by means of the locking cams 48 of the cylindrical shafts 47. When this result is attained, the air drawn in by the pumps is compelled, in order to escape, to pass through the little secondary collector 53, lifting the ball valve 54.

For the re-charging of the high pressure reservoir 42, the operator can produce the effect, either with the upper cylinders or with the lower cylinders, simply by closing one of the delivery valves to the cylinders of the tubes 34.

The present invention comprises a modification including hemispherical compression chambers, which involves the provision of special distributors for the motor and for the pump. Each of these distributors comprises a sleeve 92 concentric to the pump cylinder. (Figs. 5, 6, 7.)

This sleeve is provided with rollers 93 arranged at regular intervals around its axis, and rotating in a track on the incline 94 the height of which is equal to the course which the sleeve 92 is arranged to take.

The aforesaid sleeve is moreover provided with a projection 92' co-operating with the circular half-teeth 92" made in one piece with a rod 95 which can rotate on its axis. This rod 95 is controlled by a connecting piece 96 co-operating with a cam 97 keyed upon a shafting 98 which receives its motion from the main shaft 73 by means of the cone gears 99.

The operation of the mechanism above described is as follows:

The cam 97 acting upon the member 96 pushes the rod 95 which in turn by means of the half-teeth 92" and the tooth 92' causes the sleeve to rotate. During this rotation the rollers 93 travel upon the inclines 94 imparting thus to the sleeve a rising motion. The combination of these two controls results in giving to the sleeve, a rising helicoidal motion.

A spring 100 returns the sleeve to its original starting point.

Another feature of the invention herein described consists in the operation of the air pump.

The air pump 101 draws in the outer air through the openings 102, and forces the said air through the conduit 103 into the gear box which communicates through the pipe 105 with the compression ports 107.

In order to obtain the compression of the air required for the starting the operator proceeds as follows;

In the case of a single cylinder the action is one of simple effect and there is given alternately a pump stroke into the gear box and a pump stroke into the high pressure reservoir. In order to obtain these alternate pump strokes one first causes the pump 101 to draw in normally but leaving the compression ports 107 closed; thus the air in order to escape is obliged to overcome the resistance of the valve 108 and passes into the high pressure reservoir through the pipe 109. The next stroke of the pump is given in ordinary course and so on. With regard to the construction of the air pump for the purpose of enabling it to act with double effect like the motor cylinder, the following arrangement is adopted. (Fig. 8.)

The shape of the piston 165 is shown in the drawing and the lower compression chamber 166 has correspondingly a cylinder bottom 167. The inlet ports 168 and the outlet 169 are doubled likewise the distributors 170, 171, the suction tubes 172, 173 and the compression tubes 174, 175. Each of the distributors 170, 171 is controlled by a corresponding cam 176, 177 one at least of these cams having a sloping surface and being conformed so as to ensure the stoppage at the dead point of the distributor which it controls.

This improved construction of the air pump is of particular interest in the case of aviation motors intended to operate at great altitudes.

As the drawing shows (Fig. 9) in the case of a motor with a single cylinder there can be obtained a half speed action of the cam shaft 178; this arrangement enables the motor to act as a motor with a single motor stroke so that the pump can operate as an air compressor.

This result is obtained in the following manner:

The rod 179 is caused to slide in the cam shaft 178 and by this motion the cam controlling the distributor of the compressor is displaced, together with the cam controlling the distributor of the upper cylinder and the cam controlling the injector delivering the fuel in the same cylinder, all these cams being rigidly connected to the rod 179.

In this manner, there can be put into operation, at will, one or the other of guides *a* or *a'* of cam 176, and *b* or *b'* of cam 177. The upper guides *a* and *b* of these two cams present two bosses *c*, and *c'* and the cam turning with a speed one half that of the motor shaft, the distributors 170 and 171 (Fig. 8) would have a movement of the same frequency as that of the pistons. The 10 guide *a'* presents a single normal boss *c* and a lesser boss *c'*, and gives on one stroke out of two, to distributor 170, a movement of full amplitude, and, on one stroke out of two, a movement of reduced amplitude, 15 sufficient for opening the admission port, but insufficient to open the outlet port. Also, the guide *b'* of the lower cam, presents no boss, and corresponds to complete immobility of the distributor 171, in the position of opening of the inlet ports. 20

It is possible, according to the positions given to cams 176, and 177, by the mechanician, to make the motor function in the following different manners.

25 When the cams present guides *a* and *b* to the rollers of the distributors 170 and 171, the pump is doubled acting, pumping air at low pressure only.

When guides *a'* and *b* are in operation, 30 in the same manner as above, (i. e. low pressure only), the upper face has a mixed function. One stroke out of two pumps low pressure, and the following stroke, high pressure. On the first stroke, when boss 35 *c* acts, distributor 170 goes to the end of its movement, and opens the port 169, by which the compressed air passes to the low pressure container. On the next stroke, the low boss *c'* comes into action, and first 40 opens the inlet port 168, but does not reach outlet port 169. Air is thus highly compressed, until it attains sufficient pressure to raise an automatic valve, (not shown, but similar to 108 of Fig. 5) which communicates with the high pressure container. Thus the operation is, on one stroke out of two, high pressure and the next, low pressure.

When guides *a'* and *b'* are in operation, 50 the upper face of the pump piston has a mixed operation, while the lower face is without action; the lower inlet port 168, being kept closed.

Finally, when guides *a* and *b'* are in 55 operation, the upper face of the piston operates on low pressure only, the lower face being inoperative, because of the constant opening of the lower inlet port 168.

This capability of controlling the functioning of the motor, adapts itself to variable conditions of power and of air, and is of particular advantage where the motor is to be used in airplanes which must fly at variable heights.

60 65 The special method of arrangement of

the vertical shaft 98 forms also one of the features of my improved system. It controls, by means of suitable helicoidal gearing 110 and 111 a shaft 112 which actuates the magneto and a water circulating pump 70 of known construction. The cam shaft 98 possesses in addition to the cam 97 which actuates the distributor of the pump the further cams 113 which control the distributors of the motor, the cams 114 which control the starting; the cams 115 which control the admission of the vapourizing air, and finally the cams 116 which control the injection of the fuel. The cam shaft 98 also ensures the control of the fan 117 by the interposition 80 of a conical coupling 118, 119 with strong friction.

It should also be observed that the invention in question ensures the commencement of the admission of pure air into the motor cylinder only at the moment when the escape of the burnt gases is almost finished. It is only when the exit openings are masked by the piston that the petrol or other combustible liquid arrives in the motor.

Having now particularly described the nature of my said invention, and in what manner the same is to be performed, what I claim is:

1. A two stroke, double acting, internal combustion engine, comprising, a motor piston and a pump piston on a single rod, a low pressure air reservoir, for receiving low pressure air for the known feeding and scavenging of the motor, a high pressure air reservoir for receiving high pressure air for the known starting with compressed air, the pump piston being arranged, for feeding at times, the low pressure reservoir, and at times, the high pressure reservoir, a cut off means for the low pressure reservoir, change of feed from low pressure to high pressure, being controlled solely by the operation of said cut off means.

2. A two-stroke double-acting internal combustion engine, comprising a pair of aligned cylinders, a motor piston in one of said cylinders, an air pump piston in the other of said cylinders, a piston rod connecting said pistons to operate in unison, and distributing means comprising a sleeve rotatably mounted upon the pump cylinder and provided on its periphery with rollers, inclined tracks for said rollers, and means for automatically rotating said sleeve in one direction, whereby said rollers traveling upon said inclined tracks impart a rising motion to said sleeve.

3. A two-stroke double-acting internal combustion engine, comprising a pair of aligned cylinders, a motor piston in one of said cylinders, an air pump piston in the other of said cylinders, a piston rod connecting said pistons to operate in unison, and distributing means comprising a sleeve

- mounted for rotation upon the pump cylinder, and provided upon its periphery with rollers, inclined tracks for said rollers, and means for rotating said sleeve in opposite directions, comprising a projection on said sleeve, a sliding rod having a pair of teeth cooperating with the projection on the sleeve, and means for reciprocating said rod in opposite directions.
- 10 4. A two stroke, double acting, internal combustion engine, comprising, a plurality of motor pistons, each of which has a double acting pump piston coupled therewith, a high and a low pressure air reservoir, for receiving air from the pump piston, distributors controlling the air for the pump pistons, said distributors being controlled by slidably adjustable cams, each cam having two appropriately formed guide portions, whereby, the operation of the pump piston ²⁰ can be controlled for double acting low pressure pumping, for single acting low pressure and for single acting low pressure pumping on one of two strokes, and for high-pressure pumping on the other, this latter ²⁵ being due to one of the distributors being stationary, and the other distributor opening an outlet port, on only one of the two strokes.
- 15 In testimony whereof I have signed my ³⁰ name to this specification in the presence of two subscribing witnesses.

JULES LEROY.
